Robert J. Fiers, 8195 Lesner Ave.,
Van Nuys, Calif. 91406

Filed Mar. 7, 1968, Ser. No. 10,890

Term of patent 14 years

(Cl. D41—1)

FIGURE 1 is a side elevational view of an adjustable stabilizing support for recreational vehicles showing my new design;

FIGURE 2 is a side elevational view thereof, the opposite side being the mirror-image thereof;

FIGURE 3 is a top plan view thereof;

FIGURE 4 is a bottom plan view thereof;

FIGURE 5 is a side elevational view thereof as seen from the right side in FIGURE 2; and

FIGURE 6 is a side elevational view thereof as seen from the left side of FIGURE 2.

The broken line showings of a support post and vehicle portion are merely for illustrative purposes.

I claim:

The ornamental design for an adjustable stabilizing support for recreational vehicles, substantially as shown and described.
